UNITED STATES PATENT OFFICE.

MACK H. LEVY AND HERMAN WANDER, OF NEW YORK, N. Y.

WATCH.

Application filed March 11, 1924. Serial No. 698,376.

To all whom it may concern:

Be it known that we, MACK H. LEVY and HERMAN WANDER, citizens of the United States, residing at New York city, in the county of New York and State of New York, have invented certain new and useful Improvements in Watches, of which the following is a specification.

Our invention relates to a new and improved form of watch.

One of the objects of our invention is to provide a watch which can be used in the ordinary manner and which can also be used as a clock.

Another object of our invention is to provide a combined device of the character above mentioned which can be simply and efficiently manufactured and whose parts can be readily moved into a position in which the device serves as a clock.

Another object of our invention is to provide a device of the character above described which shall be compact and which shall have a neat and artistic appearance.

Other objects of our invention will be set forth in the following description and drawings showing two embodiments thereof.

Fig. 1 is a perspective view showing the device in the closed position.

Fig. 2 is a perspective view showing the said device in the open position.

Fig. 3 is a vertical central section, partially in elevation.

Fig. 4 is a section on the line 4—4 of Fig. 3.

Fig. 5 is a top view with the upper half of the case removed.

Fig. 6 is a central sectional view showing the device in the open position.

Fig. 7 shows a device similar to that illustrated in Fig. 1 in which the upper half of the case has a glass front fitted therein.

The device consists of a watch case comprising a lower part 3 and an upper part 4 connected by an ordinary hinge 6. The lower part 3 is provided with a bow 1 and a detent member 2 which is connected to the blade spring 20. The blade spring 20 is secured to the front of the lower member 3 by ordinary lugs 21 and 22 and it has the detents 18 and 19 connected thereto. The said detents 18 and 19 serve to hold the watch in the closed position in the well known manner.

The movement carrying portion of the watch 7 is pivoted to the front part of the

lower member 3 by means of a pin 12 whose ends are suitably connected to the lower member 3. The movement carrier 7 is provided with lugs 25 and 26 which fit upon the pin 12. An ordinary spiral spring has one end 15 held by a lug 14 which is suitably connected to the lower member 3. The other end 24 of the said spiral spring S is held in a lug 23 which is connected to the lower part of the movement carrier 7.

The torsion of the spiral spring S normally urges the movement carrier 7 to the position shown in Fig. 2. The rear end of the movement carrier 7 is provided with pins or lugs 10 and 11 which slide in grooves 16 of the upper member 4.

Hence, when the detent member 2 is pushed inwardly so as to release the upper member 4 of the watch case, the spiral spring S operates to upwardly revolve the movement carrier 7 and this causes the upper movement of the member 4 until the parts assume the positions shown in Fig. 2.

In this position the device can be placed upon a desk or any other convenient place, where it serves as a clock.

The numbers upon the dial can be rendered luminous in the well known manner.

The embodiment shown in Fig. 7 has a glass front so that it is not necessary to open the device to see the dial.

The movement carrier 7 is provided with the ordinary winding detent member 8 and other parts of the device may be made according to the ordinary methods of constructing watches.

It will be noted that since the pin 12 is located wholly within the lower watch case member 3, that this pin and the associated spiral spring remain invisible when the watch is opened, that is, when it occupies the position shown in Fig. 2. The location of the spiral spring in connection with the pin 12 makes it possible to make the watch as thin as the ordinary watch. The pins 10 and 11, in combination with the grooves 16 of the upper watch member, act as retaining means to prevent the separation of the movement carrier from the cover 4, when the watch is in the open position.

We have shown a preferred embodiment of our invention but it is clear that numerous changes and omissions could be made without departing from the spirit of our invention.

We claim:

1. A watch comprising a first watch case member, a movement carrier pivoted to said first watch case member adjacent the front thereof by means of a hinge located within said first watch case member, and spaced from the front wall of said first watch case member, a second watch case member connected to said first watch case member by means of a hinge located at the rear of the 5 said first watch case member, spring means comprising a spiral spring associated with the first mentioned hinge and adapted to cause said movement carrier and said second watch case member to be moved away from 10 said first watch case member to an open position of said watch, and retaining means independent of said spring means and adapted to hold said movement carrier and said second watch case member together in the 15 open position of said watch.
2. A watch or the like comprising a first watch case member having a second watch case member hinged thereto at the rear thereof, a movement carrier connected to 20 said first watch case member adjacent the front thereof by a hinge, spring means associated with said hinge and adapted to urge said movement carrier away from said first watch case member, the said second watch case member and the said movement carrier having respective connecting means relatively 25 slidably to each other and adapted to hold said movement carrier and said second watch case member together in the open position of said watch.
3. A watch or the like comprising a lower member having a cover member hinged thereto at the rear thereof, a movement carrier 30 connected to the said lower member adjacent the front thereof by a hinge, spring means associated with said hinge and adapted to urge the said movement carrier away from the said lower member, the said cover member having longitudinal grooves and the said movement carrier having pins 35 adapted to slide in the said grooves.
4. A folding watch case of the character described, comprising a hinged cover and body portion having guideways, a movement case hinged to said cover and means for 40 guiding and retaining the free end of said case in said body portion, said means comprising projections adjacent the free end of the movement case and fitting into said guideways.
5. A watch case comprising in combination a watch, and an outer case composed of two hingedly connected parts, a hinge connecting the watch with the upper part 45 of said outer case, a spring in said hinge, and laterally projecting studs on opposite sides of the watch adapted to slide on the inner edges of the lower part of the outer case for guiding the watch, so that when the outer case is in the open position the two parts of the same form a watch stand and the watch adjusts itself automatically into an inclined position adapted for reading the 50 position of the hands, the lower part of the outer case serving as a watchstand base and the upper part of the outer case serving as support.

In testimony whereof we hereunto affix our signatures.

MACK H. LEVY.
HERMAN WANDER.
